CENTRALIZED TRAFFIC CONTROLLING
SYSTEM FOR RAILROADSSedgwick N. Wight, Rochester, N. Y., assignor to
General Railway Signal Company, Rochester,
N. Y.

Application January 25, 1935, Serial No. 3,476

13 Claims. (Cl. 246—3)

This invention relates to centralized traffic controlling systems for railroads, and more particularly pertains to a system of the type employing direct line wire control for the switches and signals of such a system.

The present invention proposes to govern the operation of a railroad track switch over one polarized control circuit, and to govern the operation of the signals associated therewith over another polarized control circuit. The polarized control circuit for the control of the signals is contemplated as having superimposed thereon the indication of the track switch correspondence with its switch controlling means and also the indication of whether the signals are at stop or clear.

One object of the present invention is to provide means associated in a simple manner to accomplish the above mentioned purposes, while another object of the invention is to provide such signal control and superimposed indications in a manner that the signal control can be transmitted only when the switch is in correspondence with its control means.

Another object of the invention is to provide for the indication of the condition of the signals by the use of high and low currents on the signal control circuit, to thereby increase the capacity of the signal control circuit.

Other objects, purposes and characteristic features of the present invention will be in part obvious from the accompanying drawings and in part pointed out, as the description of the invention progresses.

In describing the invention in detail, reference will be made to the accompanying drawings, in which like reference characters designate corresponding parts throughout the several views, and in which:

Fig. 1 illustrates in a diagrammatic manner one embodiment of the present invention as applied to the control of traffic over a single railroad track switch;

Fig. 2 illustrates in a diagrammatic manner a simplified form of the signal control and indication illustrated in Fig. 1;

Fig. 3 illustrates in a diagrammatic manner a modified form of signal control and indication;

Fig. 4 illustrates in a diagrammatic manner, a modified form of control for the signal control circuit at the field station to superimpose the signal indication, which modified form may be employed in connection with either Fig. 2 or Fig. 3.

Although the traffic controlling system of the

present invention may be applied to various track layouts involving conflicting routes and non-conflicting routes as well as various other conditions encountered in signalling practice, it has been specifically illustrated in the present embodiment as applied to a single track switch with its signals, which switch and signals are preferably associated with suitable automatic signalling either of the automatic block signal type as shown, for example, in my pending application, Ser. No. 120,423, filed July 3, 1926, or in connection with interlocking type of signalling as shown, for example, in my pending application, Ser. No. 540,596, filed May 28, 1931.

With reference to the accompanying Fig. 1 of the drawings, a railroad track switch TS is illustrated as connecting the rails of a main track to the rails of a diverging or turn-out track. This track switch TS is operated by a power driven switch machine SM which may be of any suitable type, such, for example, as disclosed in the patent to W. K. Howe, Patent No. 1,466,903, dated September 4, 1923. This switch machine may also be provided with a dual control selector to permit hand operation of the track switch, as shown, for example, in the patent to W. K. Howe, Patent No. 1,852,573, dated April 5, 1932.

The main track adjacent the track switch TS and a portion of the diverging track to the foul point comprises the usual detector track circuit of the closed circuit type, the specific details of which have been omitted for the sake of simplicity in the disclosure. However, the opposite ends of the detector track section are provided with suitable signals for governing traffic over such track section including the track switch, as well as the subsequent track sections usually governed by such signals.

Traffic over the track switch TS in an east bound direction is governed by the signals 1A and 1B on the main track and onto the diverging track respectively; while signals 2A and 2B are provided for governing traffic in a west bound direction on the main track and off the diverging track respectively.

These signals 1A—1B and 2A—2B preferably have suitable automatic signalling associated therewith; but for the sake of simplicity in the present disclosure, the signals have only been indicated as controlled by suitable signal controlling relays.

More specifically, the signal 1A is indicated as controlled by the signal controlling relay 1AG to display stop while back contact 43 is closed and to display clear while front contact 43 is closed.

Similarly, the signal 1B is controlled by relay 1BG to display stop while back contact 42 is closed and to display clear while front contact 42 is closed. The signals 2A and 2B for the opposite direction are similarly controlled by relays 2AG and 2BG having controlling contacts 44 and 45 respectively.

When all of the signals are at stop by reason of the deenergization of their respective signal control relays G (with suitable preceding designations), a signal at stop relay RP is energized by a circuit closed from (+), through a circuit including back contact 38 of relay 1BG, back contact 39 of relay 1AG, back contact 49 of relay 2AG, back contact 41 of relay 2BG, winding of relay RP, to (-). The relay RP has a contact 39 which is employed to govern the signal control circuit in a manner to transmit the signal indication, as hereinafter described in detail.

The track switch TS and the switch machine SM are preferably provided with point detector contacts (not shown) of some suitable type, as disclosed, for example, in the patent to C. S. Bushnell, Patent No. 1,517,236, dated November 25, 1924. These point detector contacts are employed to energize with current of one polarity a switch position repeating relay WP of the usual polar neutral type when the track switch is in an extreme normal locked position, and to energize it with current of the opposite polarity when the track switch is in an extreme reverse locked position, or to deenergize this relay WP whenever the track switch TS is unlocked or the switch machine SM is in operation. Such control of the relay WP is well understood and is merely indicated by a dotted line extending from the relay WP to the track switch TS and switch machine SM.

A polar neutral relay WZ, preferably of the magnetic stick type, is governed from the control office over a suitable polarized line circuit by a switch machine control lever SML in accordance with the position of its contact 10. Such control has been merely indicated by a dotted line, but any suitable type control may be employed such, for example, as shown in my pending application Ser. No. 737,780, filed July 31, 1934.

The polar neutral relay WZ is provided with a contact 13 which is indicated as controlling the switch machine SM, which control has been merely indicated by a dotted line, but this control may be of any suitable type, it being understood that suitable approach locking and time releasing therefor and other adjuncts of a signalling system are preferably employed in connection therewith so that the track switch TS cannot be operated while such operation is unsafe.

Neutral relays NWP and RWP are associated with the relays WP and WZ to indicate when the switch control relay and track switch are in corresponding positions. More specifically, the relay NWP is energized whenever the relays WZ and WP are in corresponding normal positions by a circuit closed from (+), through a circuit including front contact 24 of relay WZ, front contact 25 of relay WP, polar contact 26 of relay WP in a right hand position, winding of relay NWP, polar contact 27 of relay WZ in a right hand position, to (-). On the other hand, when the relays WZ and WP are in corresponding reverse positions, the relay RWP is energized by a circuit closed from (+), through a circuit including front contact 24 of relay WZ, front contact 25 of relay WP, polar contact 28 of relay WP in a left hand position, winding of relay RWP, polar contact 27 of relay WZ in a left hand position, to (-).

A polar neutral relay SZ having two windings is governed from the central office over a polarized control circuit including line wires 8 and 9. This relay SZ is employed to select by contacts 32 and 33 in cooperation with contacts 34, 35, 36 and 37 of relays NWP and RWP, one of the four signal control relays G, such as relays 1AG-1BG and 2AG-2BG.

In the central office, the switch machine control lever SML is provided with a contact 11 which is employed to control a correspondence stick relay CS which in turn governs a correspondence indicator 15 suitably located on the control panel adjacent the switch machine control lever SML.

A signal control lever SL is suitably located upon the control panel in the central office; and, through its contact 12 supplies positive or negative potential to the signal control line circuit, or deenergizes such circuit so as to suitably control the polar neutral signal control relay SZ at the field station.

A marginal neutral relay SK is employed in connection with a signal lever repeating relay SLP to provide the correspondence and signal indications as transmitted from the field station over the signal line circuit. These two relays in combination are employed to control the indicators 15 and 16 which are suitably located on the control panel.

A suitable source of energy is indicated by battery 47 at the field station for supplying potential to the signal control and indicating circuit and is shown as having a center or mid-tap connected to the common return line wire 9. In the control office, a battery 46 supplies positive and negative potential to bus wires 5 and 7 respectively, and a mid tap is connected to a common bus wire 6 and the common return line wire 9.

Various circuits not connected with the line circuit are indicated as being supplied with energy from a suitable source indicated by (+) and (-) for the opposite terminals of such source. It is to be understood in this connection that various circuits may be supplied with energy from the same source or different sources than those shown in accordance with the practical application of the system of the present invention. Also, those sources which have been indicated as direct current may be changed to alternating current as desired, by suitably substituting alternating current relays properly controlled to embody the principles of the present invention.

It is believed that the invention will best be understood by further description being set forth from the standpoint of operation.

55

Operation

With the system in its normal condition, the signals 1A-1B and 2A-2B are at stop by reason of the deenergization of the signal control relays G (with suitable preceding numerals and letters). Also, the track switch TS is shown as being in a normal main track position.

Assuming that the switch machine control lever SML has not been operated since the last operation of the track switch TS, then the correspondence stick relay CS is energized by a circuit closed from (+), through a circuit including its front contact 14, lower winding of relay CS, contact 11 of lever SML in a normal position, to (-).

The switch position repeating correspondence relays NWP and RWP have energizing circuits previously pointed out, and under normal conditions only the relay NWP is energized.

Let us assume that the operator moves the

70

75

75

switch machine control lever SML to a reverse position operating the contacts 10 and 11 to their dotted line positions. With traffic conditions proper, all automatic control in accordance with traffic being omitted for the sake of simplicity, the relay WZ is energized so as to operate its polar contacts 13 and 27 to reverse dotted line positions and its neutral contact 24 may or may not be momentarily caused to assume a deenergized position depending upon whether the relay WZ is of the usual polar neutral type relay, or whether its neutral armature is of the retained type. The contact 13 in a reverse position causes the switch machine SM to unlock the track switch TS and operate it to a reverse position in which it is again locked up. While the track switch TS is in an unlocked condition, the relay WP is deenergized opening its neutral contact 25.

As soon as the contact 11 of lever SML is operated to its dotted line reverse position, the lower winding of the relay CS is deenergized and a circuit is closed through its upper winding which is differentially connected with respect to its lower winding. This circuit includes front contact 14, so that the magnetic flux in the relay CS is quickly reduced to zero and the contact 14 immediately drops away opening such energizing circuit and causing the relay CS to remain deenergized until its pick-up circuit is closed. The correspondence indicator 15 is now energized through back contact 14, thereby indicating to the operator that the control lever SML has been moved out of correspondence with the track switch TS.

As soon as the contact 27 of relay WZ assumes a position out of correspondence with the polar contact 26 of relay WP, the switch position repeating correspondence relay NWP is deenergized which closes back contact 29. This causes the relay SK in the central office to be energized by a circuit closed from the positive terminal of the battery 47, through a circuit including back contact 29 of relay NWP, back contact 28 of relay RWP, line wire 8, upper and lower windings of relay SK in multiple, contacts 22 and 23 of relay SLP in multiple, common bus 6, common return line 9, to the mid-tap of battery 47.

The relay SK has its windings so designed that when both the upper and lower windings are energized by half potential supplied by the battery 47, its contacts are picked up, but, if only one of its windings is energized with such a potential then its contacts drop away. Likewise, if only one of its windings, such as the upper winding, is energized from half potential from the battery 46, its contacts do not pick up; but, when half potential from the battery 46 and half potential from the battery 47 are connected in series through its upper winding, then its neutral contacts pick up.

Thus, as the circuit above traced for the relay SK includes both of its windings in multiple, its neutral contacts pick up. This closes a pick-up circuit for the relay CS from (+), through a circuit including front contact 19 of relay SK, upper winding of relay CS, contact 11 of lever SML in a reverse dotted line position, to (-).

A circuit is also closed from (+), through a circuit including front contact 17 of relay SK, back contact 18 of relay SLP, indicator 15, to (-). So long as the track switch TS is unlocked or out of correspondence with the lever SML, the out of correspondence indicator 15 will be illuminated.

When the track switch TS is completely oper-

ated to its reverse locked position, then the relay WF is energized with the reverse polarity closing front contact 25 and operating contact 26 to its dotted line position which then energizes the relay RWP by a circuit previously pointed out. Upon energization of relay RWP and the opening of back contact 28, the relay SK is deenergized which opens front contact 17. This deenergization of the indicator 15 advises the operator that the track switch TS is in correspondence with its control lever SML.

The operation of the system upon controlling the track switch TS to its normal position from its reverse position is merely an inverse function of the operation already described, and thus will not be set forth in detail.

Let us assume that the system is in its normal condition, and that the track switch TS is unlocked and operated by hand to its reverse position, which may be accomplished by a suitable dual control selector, as above mentioned. As soon as the track switch TS is unlocked, relay WP is deenergized opening front contact 25 which in turn deenergizes the relay NWP. The closure of back contact 29 energizes the relay SK by the circuit above pointed out, so that the out of correspondence indicator 15 is illuminated. Such condition will be maintained even when the track switch TS is in its reverse locked position energizing the relay WP with the opposite polarity by reason of the fact that polar contacts 26 and 27 are out of correspondence and neither of the relays NWP and RWP can be energized.

Assuming that the system is in its normal position, we may now consider how the signal control lever SL controls the signals and its interrelation with the switch correspondence indication above described.

Let us assume that the operator moves the lever SL to a right hand position to clear the signal 1A for traffic in an east bound direction over the track switch TS in a normal position. This closes an energizing circuit for the signal lever repeating relay SLP from the positive bus 5 through a circuit including contact 12 in a right hand position, back contact 20 of relay SK, winding of relay SLP, to the common bus 6. This causes the relay SLP to pick up and close front contact 21 so that the relay SLP will remain energized so long as the lever SL remains in an operated signal clearing position, irrespective of whether the relay SK opens back contact 20 or not.

In this connection, it may be well to note, that, if the track switch TS is unlocked thus energizing the relay SK, as previously pointed out, the open back contact 20 prevents the energization of relay SLP. This arrangement prevents any interference between the switch out of correspondence indication and the signal control, which sequence is perfectly permissible inasmuch as it would be undesirable to transmit signal control if the track switch were not in an extreme locked position in correspondence with its control lever.

Assuming, however, that the track switch TS is in a normal locked position and that the relay SLP can be properly energized, then the picking up of the contacts of relay SLP closes an energizing circuit for the relay SZ from the positive bus 5, through a circuit including contact 12 of lever SL in a right hand position, front contact 21 of relay SLP, front contact 22 of relay SLP, upper winding of relay SK, line wire 8, back contact 28 of relay RWP, front contact 29 of relay NWP, lower winding of relay SZ, front contact 30 of

relay RP, upper winding of relay SZ, common return line wire 9, to the mid-tap of battery 46.

The energy which flows in this circuit is insufficient to actuate the contacts of the relay SK, as previously mentioned. However, the current is sufficient to cause the actuation of the contacts of the relay SZ, as the windings of relay SZ are so connected that the magnetic fluxes in these windings are additive.

10 The energization of the relay SZ with current flowing in the circuit just traced, causes its polar contacts 31 and 33 to be actuated to right hand positions and its neutral contacts to be picked up. Thus, an energizing circuit is closed for the 15 signal control relay 1AG by a circuit closed from (+), through a circuit including front contact 32 of relay SZ, polar contact 33 of relay SZ in a right hand position, front contact 35 of relay NWP, windings of relay 1AG, to (-). The energization 20 of relay 1AG causes the red or stop indicator of the signal 1A to be deenergized and the green or proceed indicator to be energized by reason of its contact 42.

25 The energization of the relay 1AG opens back contact 39 deenergizing the signal repeating relay RP. The opening of front contact 30 of relay RP disconnects the upper winding of the relay SZ from the signal control circuit above traced, and includes the right hand portion of battery 47 in 30 such circuit by reason of the closure of back contact 30 with polar contact 31 in a right hand position. This circuit may now be traced from the positive terminal of battery 46, positive bus 5, lever contact 12 in a right hand position, front 35 contact 21 of relay SLP, front contact 22 of relay SLP, upper winding of relay SK, line wire 8, back contact 28 of relay RWP, front contact 29 of relay NWP, lower winding of relay SZ, back contact 30 of relay RP, polar contact 31 of relay SZ in a right hand position, negative terminal of battery 47, mid-tap of battery 47, return line wire 9, to the mid-tap of battery 46.

40 Thus, with half potential from each of the batteries 46 and 47 connected in series upon the deenergization of the signal repeating relay RP, sufficient current flows through the lower winding of relay SZ to maintain it in an energized condition, while the current value flowing through the upper winding of relay SK causes its neutral contacts to be picked up. Such picking up of contact 20 is immaterial to the energization of relay SLP for reasons previously mentioned; but the picking up of contact 17 with relay SLP energized 45 closes a circuit from (+), through a circuit including front contact 17, front contact 18 of relay SLP, indicator 16, to (-). This energization of the indicator 16 advises the operator that a signal is cleared in accordance with the positions of the control levers SML and SL.

50 The removal of the upper winding of relay SZ upon the inclusion of the battery 47 in the signal control circuit is for the purpose of preventing the relay SZ from becoming overenergized and also for the purpose of causing a greater increase of current in the control circuit. In other words, the added current which flows, due to the increase of potential and the decrease in resistance in the circuit upon the insertion of battery 47, merely compensates for the removal of the upper winding 55 of relay SZ, thereby causing the ampere turns of the relay to remain substantially constant.

60 The relay SZ is sufficiently slow acting to remain picked up during the shift from the upper winding to the battery 47.

65 It is apparent that if the lever SL were operated

70 to its opposite position that opposite potential would be applied to relay SZ operating its polar contacts to opposite positions, so that the opposite portion of battery 47 would be included in series with the opposite portion of battery 46 upon the deenergization of relay RP, thereby accomplishing the energization of indicator 16 in the control office, as above pointed out in connection with the signal 1A.

75 It is believed unnecessary to point out the operation necessary to clear the various signals in further detail than to state that the signal lever SL in a right position clears east bound signals 1A or 1B depending upon the position of the track switch TS, while in a left hand position it clears 15 the signals 2A and 2B depending upon the position of the track switch TS.

80 The restoration of a signal to a stop condition is accomplished, as is readily apparent, by the return of the signal lever SL to a central stop position which in turn deenergizes the relay SZ and the particular signal relay G which is energized. When all of the signals are at stop the relay RP is energized and the system is thereby restored to its normal condition.

85 *Fig. 2. (Simplification of Fig. 1).*—This figure 90 illustrates the principles of the signal control and signal indication shown in Fig. 1 but disassociated from the switch out of correspondence indication. Similar parts in the system are given 95 the same reference characters as in Fig. 1. The relay SK² is similar to the relay SK of Fig. 1 but is shown as having but a single winding. The armature of relay SK² requires a predetermined number of ampere turns to pick it up. The current supplied by either part of battery 46 is insufficient to energize the relay SK² to such a degree, but when the proper part of battery 47 is added in series, sufficient current flows to give the required ampere turns to pick its armature up. 100 This is the same relation between the signal control and indication currents as exists for Fig. 1.

105 When the relay SK² is picked up, it closes front contact 50 to energize the signal indicator 16 to advise the operator that a signal is clear. 110 When the signal control circuit is closed and is energized with half potential from the battery 46, the relay SK² does not respond, but the relay SZ responds, as described in connection with Fig. 1.

115 Upon the clearing of the selected signal the relay RP is deenergized inserting the proper section of battery 47. Thus, with half potential from battery 47 and half potential from battery 46 connected in series, sufficient current is supplied to the relay SK² so that it is picked up giving the signal clear indication. Contact 30 of relay RP controls the exclusion of the upper winding of relay SZ and the insertion of the battery 47 in the signal control circuit, while the 120 polar contact 31 of relay SZ selects the particular section of battery 47 to be included.

125 The specific control of the signals will readily be understood by reference to Fig. 1 and its description.

130 *Modification of Fig. 3.*—Similar parts in this Fig. 3 are given the same reference characters as in Fig. 1, but as the relays SK³ and SZ³ have slightly different control, they have been given 135 distinctive exponents. This modified system also disassociates the signal control and indication from the out of correspondence switch indication disclosed in Fig. 1. The detail signal control is the same as in Fig. 1 which is indicated by re- 140

lay SZ³ being provided with the same contacts 32 and 33 for such signal control purposes.

The degree of energization of signal control and indication circuit is the same irrespective of whether the lever SL is operated to the right or to the left, the only difference being the energization of the control circuit with the opposite polarity to cause the polar contacts of the relay SZ³ to be operated to the desired positions. Thus, a description of the operation of the lever SL to a particular position will give an adequate understanding of the principles of this form of the present invention.

Let us assume that the lever SL is operated to the right. This closes an energizing circuit for the relays SK³ and SZ³ in series from the positive terminal of battery 46, positive bus 5, contact 12 in a right hand position, upper winding of relay SK³, line wire 8, upper winding of SZ³, lower winding of relay SZ³, common return line wire 9, to the mid-tap of battery 46.

At the same instant that current flow is established in the control circuit above traced, a local energizing circuit for the lower winding of relay SK³ is closed from the positive bus 5, contact 12 in a right hand position, lower winding of relay SK³ to the common bus 6.

The current which flows in the signal control line circuit is of sufficient value to cause the actuation of the neutral and polar contacts of the relay SZ³ to their proper positions, as the fluxes produced by the current in the two coils of the relay SZ³ are additive as indicated by the arrows. The fluxes produced by the current in the two coils of the relay SK³ buck each other to zero, as indicated by the arrows in the windings of relay SK³ so that the contact 51 of relay SK³ does not respond.

The closure of front contact 32 of relay SZ³ causes a signal control relay to be energized, which in turn clears a signal and deenergizes the signal repeating relay RP. The closure of back contact 52 of relay RP short circuits the lower winding of the relay SZ³ and reduces the value of resistance in the signal control circuit to such a value that the current therein is increased to a value substantially double, for example. This increased current in the signal control circuit causes the upper winding of the relay SK³ to provide a greater amount of flux than the current in a lower winding so that the difference in flux value is sufficient to actuate the contact 51 of relay SK³ to a picked up position, thereby energizing the indicator 16 and advising the operator that a signal is clear.

The increase in current in the upper winding of relay SZ³ causes a corresponding increase in the ampere turns provided by such winding which compensates for the shunting of the lower winding.

It is apparent that the return of the signal lever SL to a mid-position will restore the signals to stop and return the system to its normal condition as shown.

This modified form shown in Fig. 3 has several distinct advantages in the control of relay SK³ over the relay SK of Fig. 1, for example, insofar as the operating characteristics of the relay are concerned.

More specifically, the relay SK³ is immune to variations in the voltage of battery 46, as it is readily apparent that any change in the voltage of this battery is equally effective in both windings of the relay SK³. In other words, the relative change in the resistance of the line circuit is the

only change to which the relay SK³ is responsive.

This form of control also has the advantage that the effect of any reasonable change in resistance in the line circuit resulting from the closure of the contact 52 of relay RP can be employed to operate relay SK³ irrespective of the value of the current required for the relay SZ³. This is because the relay SK³ has a zero value of flux in its armature so long as relay contact 52 is open, but upon the closure of such contact the flux in the upper winding increases so that the difference in flux between the upper and lower windings is the amount of flux which passes through the armature of the relay SK³. This difference in flux even though it may be of a small value may be made sufficient to operate a relay armature by making the relay of a very sensitive type.

The relay SK³ is quicker in dropping away upon the picking up of contact 52 because its operating value of flux in the armature is reduced to substantially zero. In other words, the usual relation between the drop away flux and the operating flux is maintained, that is, there is the usual margin of difference between the value of flux at which the relay armature will drop away and the actual value of flux supplied to the armature at the time it is desired that it drop away, which actual value of flux in this case is substantially zero. This can be best understood by contrasting such operation with the operation of the relay in Fig. 2 where it will be seen that in certain cases when the signals are put to stop automatically (by means undisclosed in Fig. 1), the current value of the relay SK² will be reduced to a value not below the operating value for relay SZ. This operating value for relay SZ is below the drop away value of the relay SK² but the margin of difference is not as great as is the corresponding margin in the case of relay SK³.

Modification of Fig. 4.—This figure illustrates a single winding signal control relay SZ⁴ associated with the signal repeating relay RP with suitable resistors 55 and 56 in a manner that the marginal relays SK² or SK³ of Figs. 2 and 3 respectively may be suitably controlled by such an arrangement. In other words, the control illustrated for the relays SZ and RP of Figs. 2 and 3 may have substituted therefor the control illustrated in Fig. 4.

The control line circuit is contemplated as being the same as in Figs. 2 and 3 but the deenergization of the signal repeating relay RP closes back contact 54 to shunt out the resistor 56 to thereby increase the current value in the signal control circuit to a sufficient amount to cause the actuation of the signal indication marginal relay SK (with suitable exponent). Back contact 53 of relay RP includes the resistor 55 in multiple with the relay SZ⁴ so that such relay will not become overenergized.

In brief, the resistor 55 placed in multiple with relay SZ⁴ and the resistor 56 shunted from the in series connection with relay SZ⁴ reduces the resistance value of the signal control circuit to a sufficient value so as to cause the energization of the signal indication relay SK (with suitable exponent) without effecting the overenergization of the relay SZ⁴. The resistors 55 and 56 must of course be designed to fit each particular situation with each provided with proper relative resistance to give the desired control of the SK relay. The resistors 55 and 56 may be made variable resistors to thereby furnish a ready means of adapting standard apparatus to all practical conditions.

As the relay SZ⁴ controls the signals by con-

tacts 32 and 33 the same as in Fig. 1; as the relay RP is contemplated as being controlled the same as in Fig. 1; and as the signal control circuit and indication relays are located in the central office the same as in Fig. 2 or in Fig. 3, it is believed that further description relative to Fig. 4 is unnecessary.

Summary

The present invention provides, as above described, a system of signal control and indication wherein the control is accomplished by the transmission of current of one polarity or the other to a polar neutral signal control relay to cause the clearing of signals in one direction or another. The deenergization of such signal control relay holds such signals at stop. By including in such signal control circuit a relay which requires a greater current for its pick up than the initial signal controlling current, the amount of current in such signal control circuit may be increased at the field station either by the inclusion of an additional battery source in series with the one in the control office or by the reduction of the amount of resistance in the signal control line circuit, to cause the marginal relay to pick up, and thereby indicate to the operator that the signal is clear.

The present invention also provides a suitable manner in which to associate such signal control and indication with the switch control lever and the switch indication relays to transmit an out of correspondence indication to the central office without conflict. Such out of correspondence indication is transmitted by the inclusion of a suitable battery source at the field station in the signal control line circuit while it is deenergized with the signals at stop.

Having thus described a traffic controlling system arranged and organized in accordance with the present invention as one specific embodiment thereof, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the appended claims.

What I claim is:—

1. In a centralized traffic controlling system for railroads, a stretch of track, a signal for governing traffic over said stretch, a line circuit extending from said signal to a central office, means at the central office for causing current to flow in said circuit, means at said signal responsive to said current in said circuit for clearing said signal, means for increasing the current flow in said circuit throughout the time that said signal is cleared, and means at the central office responsive to said increased current in said circuit for indicating the cleared condition of said signal.

2. In a centralized traffic controlling system for railroads, a stretch of track, a signal for governing traffic over said stretch of track, a line circuit extending from said signal to a central office, a source of energy at the central office, a signal control lever for controlling the application of energy to said line circuit from said source at the central office, a relay in said line circuit responsive to current therein and effective to clear said signal, a source of energy at said signal

nal, means inserting said source at said signal into said line circuit in series with said source at the central office when said signal is cleared thereby increasing the current flow in said circuit, and a relay at the central office included in said line circuit and responsive only to said increased current flow in said line circuit.

3. In a centralized traffic controlling system for railroads, a stretch of track, a signal for governing traffic over said stretch of track in each direction, a line circuit extending from said signal to a central office, manually governable means at the central office including a signal control lever for applying current of one polarity or the other to said line circuit depending upon which of said signals is to be cleared, a polar relay included in said line circuit and responsive to one polarity or the other for clearing one or the other of said signals, means for increasing the current in said line circuit when either of said signals is cleared only provided the polar contacts of said polar relay have properly responded to the polarity of current in said line circuit as applied by said lever, and means at the central office responsive only to said increased current flow in said line circuit.

4. In a centralized traffic controlling system for railroads, a line circuit connecting a central office and a field station, a track switch at the field station, signals for governing traffic over said track switch, means at the field station for energizing said line circuit when said switch is unlocked, means at the central office for energizing said line circuit when a signal is to be cleared, means at said field station responsive to the energization of said line circuit at the control office for clearing one of said signals, means operative upon the clearing of one of said signals to increase the current flow due to the energization of said line circuit at the central office, and means at the central office responsive to current flow in said line circuit due to its energization at said field station for indicating the unlocked condition of said track switch and effective when thus responding to prevent the energization of said line circuit at the central office, said means also being responsive to said increased current flow when said line circuit is energized at said control office and one of said signals is cleared to thereby indicate that such signal is cleared.

5. In a centralized traffic controlling system for railroads, a line circuit connecting a central office and a field station, a railroad track switch at the field station, a signal for governing traffic over said track switch, a signal control lever at the central office, a signal lever repeating relay at the central office, a double winding indication relay at the central office having both windings included in said line circuit when said signal lever repeating relay is deenergized but having only one winding included in said line circuit when said lever repeating relay is picked up, a pick-up circuit for said lever repeating relay including a contact of said lever and a back contact of said indication relay, a stick circuit for said lever repeating relay including a contact of said lever and its own front contact, means supplying energy to said line circuit at the central office when and only when said lever repeating relay is picked up, means for supplying energy to said line circuit at the field station when said track switch is unlocked, a signal control relay at the field station connected in said line circuit only when said track switch is locked and

responsive to the current flow in said line circuit for controlling said signal, and means increasing the current flow in said line circuit when said signal is cleared whereby said signal indicating relay is picked up even though it has only one winding included in said line circuit.

6. In combination, a line circuit connecting a central office and a field station, a double winding indication relay in said central office, a control lever for supplying energy to said line circuit through one winding of said indication relay with current flowing in one direction and for supplying current flow in the other winding of said indication relay in the opposite direction whereby the contacts of said indication relay remain dropped away until otherwise acted upon, a control relay at the field station responsive to current flow in said line circuit, traffic controlling means controlled by said control relay, means rendered effective by said traffic controlling means to at times increase the current flow in said line circuit whereby said indication relay is caused to be picked up, and an indicator controlled by said indication relay.

7. In combination, a line circuit connecting a control office and a field station, a source of energy in said control office, a control lever for at times supplying energy to said line circuit from said source, a control relay at the field station always responsive to current flow in said line circuit for governing a traffic controlling device, means effective to reduce the resistance of said line circuit when the traffic controlling device is governed by said control relay whereby the current in said line circuit is increased, indication relay means at the control office responsive to said increased current to thereby pick its contacts up, and other means controlled by said indication relay means.

8. In combination, a control lever for controlling a railroad track switch, a stick relay having a stick circuit which is broken each time said lever is operated to a new position, a relay controlled by the track switch for indicating its unlocked condition, a pick-up circuit for said stick relay closed when said indication relay indicates the unlocked condition of the track switch, and an indicator energized whenever said stick relay is deenergized and when said indication relay indicates the unlocked condition of the track switch.

9. In combination, a control lever for controlling the operation of a railroad track switch, an indication relay caused to assume one position when the track switch is locked in correspondence with said control lever and caused to assume another position when the track switch is out of correspondence with its control by said lever or the switch is unlocked, a stick relay, a stick circuit means for said stick relay including a contact of said lever and its own front contact, a pick-up circuit for said stick relay including a contact of said indication relay in its said other position, and an indicator jointly controlled by said indication relay and said stick relay.

10. In combination, a line circuit connecting a control office and a field station, a source of energy in said control office, a control lever for at times supplying energy to said line circuit from said source, a traffic controlling device at the

field station capable of assuming either of two conditions, means effective when said traffic controlling device assumes one of said conditions to reduce the resistance of said line circuit whereby the current in said line circuit is increased, a control line relay having a winding included in said line circuit and responsive to current flow therein under both said two conditions of said traffic controlling device, indication relay means at the control office responsive to said increased current in said line circuit to thereby pick its contacts up, and other means controlled by said indication means.

11. In combination, a line circuit connecting a control office and a field station, a source of energy in said control office, a control lever for at times connecting said source of energy in series in said line circuit, a traffic controlling device at the field station capable of assuming at least two different conditions, means at the field station controlled by said traffic controlling device in one of its said conditions to increase the current flow in said line circuit, a control relay at the field station for governing the conditions of said traffic controlling device and responsive to the current flow in said line circuit at all times, an indication relay included in series in said line circuit at all times and responsive to said increased current flow to thereby pick its contacts up, and indicator means controlled by said indication relay, whereby said traffic controlling device is directly and continuously controllable by said control lever, and whereby said indication relay is directly and continuously controllable in accordance with the condition of said traffic controlling device.

12. In a centralized traffic controlling system for railroads, a stretch of railway track, a signal for governing traffic over said stretch and capable of assuming clear or stop conditions, a line circuit extending from said signal to a central office, manually governable means at the central office for at times causing current flow in said line circuit, electro-responsive means at said signal responsive to the current flow in said line circuit both when signal is cleared and when said signal is at stop, said electro-responsive means being effective to determine the clear or stop condition of said signal, means for increasing the current flow in said line circuit whenever said signal is cleared, and means at the central office responsive to said increased current in said line circuit for indicating the cleared condition of said signal.

13. In a centralized traffic controlling system for railroads, a stretch of track, a signal for governing traffic over said stretch, a line circuit extending from said signal to a central office, means at the central office for causing current to flow in said circuit, a relay at said signal having two windings connected in series in said circuit and responsive to said current for clearing said signal, means for shunting one of said windings throughout the time that said signal is cleared, and means at the central office responsive to the increased current in said circuit due to such shunting for indicating the cleared condition of said signal.
